DESIGN FOR A GOBLET OR SIMILAR ARTICLE

Andrew J. Cunningham, Snyder, N. Y.

Application February 18, 1941, Serial No. 99,068

Term of patent 7 years

To all whom it may concern:

Be it known that I, Andrew J. Cunningham, a citizen of the United States, residing at Snyder, in the county of Erie and State of New York, have invented a new, original, and ornamental Design for a Goblet or Similar Article, of which the following is a specification, reference being had to the accompanying drawing, forming part thereof.

The figure is an elevational view of the goblet, showing my design.

The ornamentation shown is continued around the stem of the goblet. The dominant feature of the design resides in the stem portion of the goblet, shown in full lines.

I claim:

The ornamental design for a goblet or similar article, substantially as shown and described.

ANDREW J. CUNNINGHAM.
